UNITED STATES PATENT OFFICE.

LUCIA J. CARLETON, OF DORCHESTER, MASSACHUSETTS.

DESIGN FOR A LADY'S SPORT-COSTUME.

58,544.

Specification for Design.

Patented Aug. 2, 1921.

Application filed January 6, 1921. Serial No. 435,524. Term of patent 7 years.

To all whom it may concern:

Be it known that I, LUCIA J. CARLETON, a citizen of the United States, residing at Dorchester, in the county of Suffolk and Commonwealth of Massachusetts, have invented a new, original, and ornamental Design for a Lady's Sport-Costume, of which the following is a specification, reference being had to the accompanying drawing, forming part thereof.

Figures I and II are side and rear views of a lady's sport costume showing my new design.

I claim—

The ornamental design for a lady's sport costume as shown.
